UNITED STATES PATENT OFFICE.

THEODORE LEWIS PATRICK, OF PAW PAW, ILLINOIS, ASSIGNOR TO HIMSELF
AND LAWREN SPRAGUE, OF SAME PLACE.

GATE.

SPECIFICATION forming part of Letters Patent No. 337,612, dated March 9, 1886.

Application filed August 14, 1884. Serial No. 149,533. (No model.)

To all whom it may concern:

Be it known that I, THEODORE LEWIS PATRICK, of Paw Paw, in the county of Lee and State of Illinois, have invented a new and useful Improvement in Gates, of which the following is a full, clear, and exact description.

Reference is to be had to the accompanying drawings, forming a part of this specification, in which similar letters of reference indicate corresponding parts in all the figures.

Figure 1 is a side elevation of my improved gate, parts being broken away. Fig. 2 is a sectional elevation of the same, taken through the line *xx*, Fig. 1. Fig. 3 is a plan view of the same, one of the side posts and its wheel and one of the rear rollers being omitted.

The object of this invention is to promote convenience in opening and closing gates and reliability in the working of said gates.

20 The invention consists in the peculiar construction and arrangement of parts, as hereinafter fully described, and pointed out in the claim.

A represents the gate, which is formed of 25 longitudinal bars attached at their ends to upright bars, or in any other desired manner.

To the rear end of the gate A, at a little distance from its top and bottom, are rigidly attached the ends of two rearwardly-projecting horizontal bars, B. The gate A slides back and forth between two parallel posts, C, and is supported by a roller, D, pivoted to and between the posts C, upon which rests a horizontal bar of the gate A, preferably one 35 of the bars above the center of the said gate.

The bars B slide between two parallel posts, E, set at a suitable distance from the side of the roadway. Each of the bars B passes between two rollers, F, pivoted to and between 40 the rear posts, to prevent the gate A from sagging at either end in whatever position the said gate may be.

The posts C are set at the side of the roadway, and the gate A shuts against a post, G, 45 set at the other side of the said roadway.

To the upper forward corner of the gate A is attached the end of a rope, H, which passes along the top of the gate, passes around a pulley, I, pivoted to the top of one of the posts 50 C, passes one or more times around a wheel,

J, pivoted to a post, K, set at the side of the roadway at one side of the forward part of the posts, passes over a pulley, L, pivoted to a bar, M, attached to the tops of the posts C, and passes one or more times around a wheel, 55 N, pivoted to a post, O, set at the side of the roadway at the opposite side of the posts C from the post K. From the wheel N the rope H passes to and around a pulley, P, pivoted to the post C, adjacent to the post O, and passes 60 thence to the rear corner of the gate A, to which its other end is attached. By this construction, by turning either of the wheels J or N the gate A can be readily opened and closed. The posts K O are designed to be set 65 at such a distance from the posts C that a person sitting in a vehicle can operate the wheel J or N to open the gate A before his horses come in contact with the said gate, and can close the gate after passing through the gateway without the gate coming in contact with his vehicle.

One or more crank-pins, Q, can be attached to the wheels J M for convenience in turning them to open and close the gate A. A 75 small wheel, R, can be placed beneath the middle part of the gate, as indicated in dotted lines in Fig. 1, to make the said gate run more steadily and easily.

I am aware that gates have been provided 80 with rearwardly-projecting bars working between rollers on posts at the side of the roadway, the gate sliding between posts and supported upon rollers between the said posts; and I am also aware that sliding gates have 85 been operated by cords wound one or more times around drums journaled in supports at the side of the road, then passed around rollers journaled in the posts, between which the gate slides, and having their ends secured 90 to opposite ends of the gate, and I therefore do not claim such invention.

Having thus described my invention, I claim as new and desire to secure by Letters Patent—

The combination, with the posts C C, connected by the bar M, the gate A, sliding between the said posts and the roadway side posts, K O, of the crank-wheels J N, journaled in the posts K O, respectively, the pulleys I P, journaled on the tops of the posts C, the 100

pulley L, journaled to the bar M, attached to the tops of the posts C, and the single cord H, having one end secured to the forward end of the gate, passed around the pulley I, one or more times around the wheel J, over the pulley L, one or more times around the pulley N, and thence around the pulley P, and its end secured to the rear end of the gate, substantially as herein shown and described.

THEODORE LEWIS PATRICK.
